Application July 23, 1942, Serial No. 452,096

13 Claims. (Cl. 164—115)

The present invention relates to an apparatus for verifying perforated tape in which the perforations are arranged according to a selected code. According to the present invention, in the course of verification, an unperforated tape is perforated by the apparatus in such a manner that only correct or verified characters are obtained. Upon completion of the process, the original tape, i. e. the tape which has been sensed, may be discarded and the newly perforated tape containing only verified data preserved.

It is an object of the invention, therefore, to verify information recorded on a tape, while at the same time reproducing or duplicating this tape.

Another object of the invention is to provide means whereby either the tape undergoing verification or the tape being prepared may be advanced or spaced, either separately or in unison, for purposes that will become apparent hereinafter.

Another object of the invention is to provide a verifying apparatus utilizing a series of depressable keys, together with means whereby if a particular character existing on the tape undergoing verification is not identical with the key which is depressed on the keyboard, the means for advancing the tape will become ineffective, or, in other words, the keyboard will become locked until such time as provision is made for correcting the information either on the verifying tape or on the duplicated tape, as the case may be.

Yet another object of the invention is to provide a means whereby should a character existing on the tape being verified not correspond with the particular key depressed, the character will not become perforated on the duplicated tape and this latter tape will not be advanced.

A further object in an apparatus of this character is to provide a means whereby a blank space on the tape being verified will be visibly or audibly indicated, as, for example, by the lighting of a lamp, the ringing of a bell, or the like.

An additional object of the invention is to provide a means whereby the perforating mechanism may be actuated from the keyboard without verification taking place, in order that the tape which is duplicated may be perforated to correct any error that may exist on the tape being verified.

It is also an additional object of the invention to provide a means whereby the original

tape may be verified without duplicating the same.

With these and other objects in view, which will become more readily apparent as the nature of the invention is better understood, the same consists in a novel construction, combination and arrangement of parts shown in the accompanying single sheet of drawings.

The figure is a schematic, diagrammatic view 10 of the apparatus showing the circuit connections therefor.

Brief description

Briefly, the invention contemplates the provision of a sensing apparatus, through which an initial record media produced from original record data and preferably in the form of a tape which is perforated according to a selected code, is periodically advanced. A perforating mechanism, including a series of magnet-controlled punches, is provided for the purpose of receiving therein a second tape, which is adapted to be perforated in the verified form according to the same code. The magnets of the perforating mechanism are adapted to be selectively controlled from a coding device and are suitably connected thereto by means of electrical circuits. The coding device is, in turn, controlled from a manually operable keyboard. The magnets of the perforating mechanism are possessed of a common or return line, preferably leading to ground, and a circuit making and breaking apparatus is arranged in series in the return line leading from the magnets and operates under the joint control of the sensing mechanism and the keyboard to establish the return circuit for the magnets when a character undergoing sensing on the first tape agrees with a particular key which is depressed at the keyboard. Conversely, the circuit making and breaking mechanism is adapted to open the common return line for the various perforating magnets when a key is depressed which does not agree with a character undergoing sensing.

While any suitable code system may be employed in connection with the present invention, the same has been illustrated in connection with the Teletypewriter code, which utilizes a four-line system of coding. Accordingly, the tape perforating mechanism employed in connection with the present invention includes four punch driving magnets for operating the character forming punches. Two additional punch magnets are employed, one for advancing the tape through the perforating mechanism and the

other for forming the usual center drive hole perforations in the tape. The tape perforating mechanism is operatively and electrically connected to a coding device and this latter device employs ten circuit closing magnets, each representative of one digit in the Arabic system for closing coding circuits leading to the four perforating magnets. An additional magnet is provided in the coding device for closing circuits leading to the tape advancing and center drive hole forming magnets in the perforating mechanism for the purpose of advancing the tape when no characters are perforated therein.

The coding apparatus is adapted to be operated directly from the keyboard according to original record material, while at the same time the coded record previously prepared from the original record data is passed through the sensing device. The sensing mechanism for the original coded data operates in conjunction with the keyboard to control the circuit making and breaking device, the function of which is to open or close the common return or ground connections for all of the magnets existing in the perforating and sensing mechanisms. Obviously, if the return lead for the magnets of the perforating mechanism is open, no perforating or tape advancing operations may be performed, while if it is closed the perforating mechanism will operate directly under the control of the coding mechanism, which is, in turn, controlled by means of the keyboard. The arrangement of the circuit maker and breaker device is such that if a particular character at an index point position on the tape undergoing verification does not agree with the key which is depressed at the keyboard, either by virtue of an error existing in the original record data or by an error on the part of the operator of the keyboard, the common return lines from the magnets of the perforating and sensing mechanisms will remain or become open, while at the same time provision is made for locking the keyboard so that no additional keys may be depressed. Provision is also made whereby if at the sensing mechanism an index point position is encountered wherein the tape is not perforated, while at the same time a key other than the spacing key is depressed at the keyboard, in addition to the circuit breaking and keyboard locking operations above referred to, a colored light will become visible to the operator.

Provision is made for utilizing the machine simply as a perforating apparatus with no regard to any verification operations whatsoever, and toward this end the common line leading from the perforating magnets may be temporarily closed by a by-pass circuit and held closed, regardless of the condition of the circuit maker and breaker, so that the keyboard will operate directly through the coding mechanism to actuate the perforating magnets.

Additionally, means are provided whereby either of the two common lines leading from the sensing mechanism or the perforating mechanism may be opened while the other remains closed in order that, upon actuation of a spacing key at the keyboard, the tape in either one or the other of these two apparatus may manually be advanced.

The sensing mechanism

Referring now to the drawing in detail, the sensing mechanism is designated in its entirety at 10, and is more or less conventional in its de-

sign. This sensing mechanism includes the usual series of sensing brushes 12 and a common contact bar 14 therebeneath. Step-by-step movement of the tape T which, as stated above, is perforated according to the selected code, and which is produced from original record data, is effected by means of a ratchet controlled tape driving drum 16. The ratchet mechanism 18 is controlled by means of a magnet DM having a common return line b.

Inasmuch as the selected code system utilizes four longitudinally extending lines for the code perforations, a corresponding number of sensing brushes 12 are employed. The various sensing brushes are electrically connected to a plurality of respective magnets CM₁, CM₂, CM₃, and CM₄ forming part of a circuit maker and breaker mechanism designated in its entirety at 20. The common contact bar 14 is connected through a pair of contacts 33 to a coding mechanism designated in its entirety at 30, the function of which will be fully set forth hereinafter.

The tape perforating mechanism

The tape perforating mechanism is designated in its entirety at 40, and it likewise is more or less conventional in design. This mechanism includes tape perforating dies 22 and cooperating punches 24, the movements of which are controlled by means of magnets MC₁, MC₂, MC₃ and MC₄. A pair of additional magnets MCS and MCD are provided for the purpose of advancing the tape T' through the apparatus and for applying drive hole perforations to the same, respectively. The magnet MCS is adapted upon energization thereof to actuate a ratchet controlled tape driving drum 26, while the magnet MCD is adapted upon energization thereof to operate a punch 28 which cooperates with a pair of dies 32. The various magnets just described are electrically connected to the coding mechanism 30 for control thereby and the common return wire or line for the magnets is connected through a pair of contacts 34 to the circuit maker and breaker 20, from whence the line may, under certain conditions, extend to ground as at 36. As stated above, the circuit connections between the coding device 30 and the various magnets at the perforating mechanism 40 are similar to the circuit connections shown in the above mentioned patent to Ward Leathers, and reference may be had to this patent for a full description thereof. It is deemed sufficient in the present instance to state that in addition to the conventional circuit connections shown in the said patent, additional circuits are controlled by the coding mechanism, the nature of which will be made apparent immediately.

The coding mechanism

The coding mechanism 30 includes a series of magnets M₁, M₂, M₃, M₄, M₅, M₆, M₇, M₈, M₉ and M₀, each magnet being provided for the purpose of controlling one or more of the magnets MC₁, MC₂, MC₃ and MC₄ to perforate the coded representation of a digit in the Arabic system in the tape T'. Toward this end, the more or less conventional circuit connections shown in the patent to Ward Leathers, above mentioned, are employed. An additional magnet MSP is provided for the purpose of actuating the magnets MCS and MCD to drive the tape and provide drive hole perforations therein, respectively. The magnet MSP is also provided with circuit connections leading to the magnet DM in the sensing device

10, in order that under normal circumstances these two magnets will become energized simultaneously together with the magnet MCS to advance the tapes T and T' periodically in unison.

In addition to the conventional coder circuits, set forth above, the coder 30 is provided with circuit connections leading to a series of magnets CM'1, CM'2, CM'3, and CM'4, associated with the circuit maker and breaker 20. The magnets CM1, CM'1; CM2, CM'2; CM3, CM'3; and CM4, CM'4, are arranged in the circuit maker and breaker mechanism in series, the magnets of each pair cooperating with each other to control various circuits, which will either permit the common line leading from the perforating mechanism 40 to extend to ground at 36, or which will open this line. These various pairs of magnets also cooperate with each other to establish or open the common line leading from the tape advancing magnet DM in the sensing device 10.

The keyboard

The keyboard 21 is also generally of conventional design and includes a plurality of depressable keys K1, K2, K3, K4, K5, K6, K7, K8, K9 and K0, adapted upon depression thereof to permit energization of the respective magnets M1, M2, M3, M4, M5, M6, M7, M8, M9 and M0 from the battery B. The keyboard also includes a depressable key KS adapted upon depression thereof to permit energization of the magnet MSP from the battery B.

A mechanical locking device, which is electrically controlled, is provided for the purpose of preventing depression of any of the keys whenever a condition obtains wherein the numeral represented by one or more perforations undergoing sensing in the sensing apparatus 10 does not agree with the numeral represented by a depressed key. This mechanical locking device is in the form of an elongated rod 42, having a series of limit stops or stop fingers 44 provided thereon adapted upon movement of the bar from a retracted position to an advanced position to be projected from a position wherein they are out of the path of movement of the various keys to a position where they are in the path of movement of these keys. Movement of the bar 42 is controlled by means of a locking magnet LM, the armature 46 of which is operatively connected to the locking bar. Two pairs of normally open contacts 48 and 50, and a single pair of normally closed contacts 52, are adapted to have their respective conditions of opening or closing reversed upon energization of the magnet LM for purposes that will become apparent shortly.

The circuit maker and breaker apparatus

As previously stated, the circuit maker and breaker apparatus 20 includes four pairs of cooperating relay type magnets which have been designated previously as CM1, CM'1; CM2, CM'2; CM3, CM'3; and CM4, CM'4. The common return wires leading from the various magnets of the perforating mechanism 40 and sensing mechanism 10 are designated at a and b respectively, and, when grounded, the common connector c for both these lines may pass through a plurality of normally closed contacts w arranged in series, the first contact being controlled by the magnet CM'4, the second contact being controlled by the magnet CM4, the third contact being controlled by the magnet CM'3, the fourth contact being controlled by the magnet CM3, etc., and the circuit passing from the last pair of contacts w,

which is controlled by the magnet CM'1, to ground. The only condition under which the above described circuit may be closed obtains when all of the various recited contacts are closed, and this condition is predicated upon the fact that all of the various magnets remain unenergized.

A second path through the circuit maker and breaker 20 exists whereby the common line c may be conducted to the ground at 36. This second path exists only at such a time as one or more of the pairs of magnets existing in the circuit maker and breaker are energized together and the remaining pairs, if any, are deenergized. This second path for the line a to ground exists by virtue of additional normally open pairs of contacts designated at x, arranged in series. If, for example, the magnets CM4 and CM'4 are both energized and the remaining magnets of the circuit maker and breaker are all deenergized, the line c will be connected through the contacts x, controlled by these first mentioned magnets, and through the various contacts w, controlled by the remaining magnets, to ground at 36. Thus, the line a will find its ground at 36 whenever both magnets of one, two, three or all the pairs of magnets existing in the circuit maker and breaker apparatus are energized and both magnets of the remaining pairs are deenergized. The only time when the line c will be opened is when one magnet of any one pair is energized and the other magnet thereof is deenergized.

Since the magnets CM1, CM2, CM3 and CM4 are controlled according to the selected code by the sensing mechanism 10, and since the magnets CM'1, CM'2, CM'3 and CM'4 are identically controlled, according to the same code, by the coding device 30, it will be apparent that conditions at the former device must parallel the conditions existing at the latter device. In other words, for example, if a character representing the numeral 5 is undergoing sensing in the device 10 and, according to the selected code, the magnets CM1 and CM2 are energized while the magnets CM3 and CM4 are not energized, the only condition obtaining which will permit the magnets CM'1 and CM'2 to be energized and the magnets CM'3 and CM'4 not to be energized will be when the key K5 in the keyboard 20 is depressed and the circuit connections controlled by the magnet M5 in the coding mechanism 30 are closed accordingly. Under these conditions, the line a will find its ground at 36 through the contacts w controlled by the magnets CM4, CM'4 and CM3, CM'3, and the contacts x controlled by the magnets CM2, CM'2 and CM1 and CM'1.

It has been explained above how the line a may or may not find a path to ground at 36 through the circuit maker and breaker mechanism 20, depending upon the condition of the various magnets associated with this mechanism. The mechanism also includes a similar set of contacts similarly arranged electrically, and designated at y and z respectively, whereby current leading through a line d from the positive side of the battery B may or may not find a path to ground at 37 through the pair of contacts 52 and locking magnet LM. The contacts y are normally closed, while the contacts z are normally open, and it is deemed unnecessary to enter into a detailed description of the manner in which these latter contacts y and z are controlled by their various operating magnets. It is sufficient to state that whenever a condition

exists in connection with any one of the pairs of magnets in the circuit maker and breaker whereby continuity is established for the line *a*, the reverse condition will exist for the line leading from the battery *B* to ground at 37 and continuity for this latter line will not be established. A converse condition exists whereby whenever continuity is not established for the line *a* through the contacts *w* or *x*, as the case may be, continuity will be established through the contacts *y* and *z*, as the case may be, to ground at 37. When such continuity is established, the magnet *LM* will become energized and the bar 42 will be shifted to a position wherein the various depressable keys of the keyboard 21 become locked so that they may not be depressed.

Simultaneously, with the energization of the magnet *LM* the pair of contacts 52 will become opened, thus breaking the magnet circuit. The magnet *LM* will remain energized, however, inasmuch as the normally open pair of contacts 48 will become closed and current will follow a path from the battery *B*, through a pair of normally closed contacts 54, through the contacts 48 and magnet *LM*, to ground at 37. The pair of contacts 50, which are also controlled by the magnet *LM*, will, upon becoming closed, cause a lamp *L* to become lighted through a series arrangement of contacts *v* controlled by the magnets *CM1*, *CM2*, *CM3* and *CM4* of the circuit maker and breaker 20, current for the lamp issuing from the battery *B* and passing through these latter contacts and the contacts 50 to ground at 39.

The circuit maker and breaker by-pass mechanism

Under certain circumstances, it may be desired to utilize the apparatus solely for manual tape perforating purposes and in such instances the sensing mechanism 10, for sensing the original recorded data, and the circuit maker and breaker mechanism will not be required. Toward this end means are provided for permanently connecting the common return line *b* of the magnet *DM* in the sensing mechanism 10 to ground at 41 through a pair of normally open contacts 56 controlled by a by-pass magnet *BPM*. The magnet *BPM* is adapted to become energized from the battery *B* through a manually controlled switch *S*, which, upon becoming closed, allows current to flow through a pair of normally closed contacts 58 to the magnet *BPM* and from thence through a pair of contacts 60 to ground at 43. Immediately upon energization of the magnet *BPM*, its circuit is broken and a locking circuit extending from the battery *B* through a pair of contacts 62 becomes effective for holding purposes. The contacts 60 are normally closed and are adapted to be opened only in the event of depression of a manually controlled push button or switch *S2*. Upon energization of the magnet *BPM*, and during such time as it is maintained energized, an additional pair of contacts 64 become closed for the purpose of energizing a lamp *L'*, which is preferably of a color different from the color of the lamp *L*. The normally closed contacts 54 will, upon energization of the magnet *BPM*, become opened, thus breaking the locking circuit extending through the contacts 52 of the magnet *LM*, in order that the shiftable bar 42 will be moved in such a direction as to free the keyboard of its locking effect and permit actuation of the various keys there-

of. Under these conditions, the keys operate in their normal manner to control the operations of the tape perforating mechanism 40. It is to be noted, however, that inasmuch as the common return line *b* of the sensing mechanism 10 is connected through the pair of contacts 56 to ground at 41, the tape *T* will be periodically advanced in synchronism with the tape *T'*. Under other conditions of operation it may be desired to employ the apparatus solely as a tape perforating device without advancing the tape *T* in the sensing mechanism 10, and under such circumstances a switch *S3* may be employed to permanently open the pair of contacts 53. A switch *S4* is provided for controlling the contacts 54 when it is desired to space the tape *T* without spacing the tape *T'*.

It is thought that from the above description the nature, operation and many advantages of the herein described duplication verification apparatus will be apparent. While there has been shown and described and pointed out the fundamental novel features of the invention, as applied to a single modification, it will be understood that various omissions and substitutions and changes in the form and details of the device illustrated, and in its operation, may be made by those skilled in the art without departing from the spirit of the invention. The invention, therefore, is to be limited only as indicated by the scope of the following claims.

What is claimed is:

1. In an apparatus of the character described, a circuit making and breaking device comprising a pair of magnets, a normally closed contact for each magnet operable upon energization of the magnet to become opened and a circuit under the control of said magnets leading through the pair of contacts in series.
2. In an apparatus of the character described, a circuit making and breaking device comprising a first series of magnets and a second series of magnets, said magnets being arranged in pairs and each pair including a magnet in the first series and a magnet in the second series, a normally closed contact for each magnet operable upon energization of the magnet to become opened and a circuit under the control of said magnets leading through the pairs of contacts of each pair of magnets in series and through the contacts of the successive pairs in series.
3. In an apparatus of the character described, a circuit making and breaking device comprising a first series of magnets and a second series of magnets, said magnets being arranged in pairs and each pair including a magnet in the first series and a magnet in the second series, a normally closed contact for each magnet operable upon energization of the magnet to become opened, a normally open contact for each magnet operable upon energization of the magnet to become closed, and a pair of circuits under the control of said magnets, one of said circuits extending through the pairs of contacts of each pair of magnets in the series and through the contacts of the successive pairs in series, and the other circuit leading through the other pairs of contacts of each pair of magnets in the series and through said other pairs of contacts of the successive pairs in series.
4. In an apparatus of the character described, a circuit making and breaking device comprising a first series of magnets and a second series of magnets, said magnets being arranged in pairs and each pair including a magnet in the first

series and a magnet in the second series, plural pairs of contacts for each magnet under the control thereof and a plurality of circuits under the control of said contacts leading through the respective pairs of contacts of each pair of magnets in the series and through the respective pairs of contacts through the successive pairs in series.

5. In an apparatus of the character described, a circuit making and breaking device comprising a first series of magnets and a second series of magnets, said magnets being arranged in pairs and each pair including a magnet in the first series and a magnet in the second series, means for selectively controlling the energization of the magnets of the first series, separate means for selectively controlling the energization of the magnets of the second series, a normally closed contact for each magnet operable upon energization of the magnet to become opened and a circuit under the control of said magnets leading through the pairs of contacts of each pair of magnets in series and through the contacts of the successive pairs in series.

6. In an apparatus of the character described, a circuit making and breaking device comprising a first series of magnets and a second series of magnets, said magnets being arranged in pairs and each pair including a magnet in the first series and a magnet in the second series, means for selectively controlling the energization of the magnets of the first series, separate means for selectively controlling the energization of the magnets of the second series, a normally closed contact for each magnet operable upon energization of the magnet to become opened and a circuit under the control of said magnets leading through the pairs of contacts of each pair of magnets in series and through the contacts of the successive pairs in series, and means for causing said circuit to by-pass said magnets.

7. In a verifying apparatus for verifying perforated data on a first record media produced from original data in corrected form on a similar second record media, an analyzing device adapted to sense perforations in the index positions of the first record media including circuits adapted to be completed under the control of said sensing means upon sensing one or more perforations in a column, a perforating mechanism for perforating corrected data on the second record media, a keyboard having depressable keys for controlling the perforating mechanism including circuits adapted to be completed under the control of said keys, means operable from said keyboard for advancing said first record media through the analyzing device and the second record media through the perforating mechanism simultaneously, and means under the joint control of said circuits for rendering the perforating mechanism inoperative when the perforations undergoing sensing in the analyzing device differ from the keys depressed at said keyboard.

8. In a verifying apparatus for verifying perforated data on a record media produced from original data in corrected form on a similar second record media, an analyzing device adapted to sense perforations in the index point positions of the first record media including circuits adapted to be completed under the control of said sensing means upon sensing one or more perforations in a column, a perforating mechanism for perforating corrected data on the second record media including a series of punch operating magnets and punches therefor, a keyboard having depressable keys for controlling said magnets in-

cluding circuits leading from the keyboard to the perforating mechanism and additional circuits adapted to be completed under the control of said keyboard, and means operable upon completion of said analyzing device circuits and said keyboard circuits for rendering said perforating mechanism inoperative when a character undergoing sensing in the analyzing device differs from the keys depressed at said keyboard.

9. In a verifying apparatus for verifying perforated data on a record media produced from original data in corrected form on a similar second record media, an analyzing device adapted to sense perforations in the index point positions of the first record media including circuits adapted to be completed under the control of said sensing means upon sensing one or more perforations in a column, a perforating mechanism for perforating corrected data on the second record media including punch operating magnets and punches therefor, a keyboard having depressable keys for controlling the perforating mechanism including circuits connecting the keyboard and perforating mechanism, additional circuits adapted to be completed under the control of said keyboard, a common terminal circuit for said magnets and means operable upon selective completion of the analyzing device circuits and said latter keyboard circuits for breaking said common terminal circuit when a character undergoing sensing in the analyzing device differs from the keys depressed at said keyboard.

10. In a verifying apparatus for verifying perforated data on a record media produced from original data in corrected form on a similar second record media, an analyzing device adapted to sense perforations in the index point positions of the first record media including circuits adapted to be completed under the control of said sensing means upon sensing one or more perforations in a column, a perforating mechanism for perforating corrected data on the second record media including punch operating magnets and punches therefor, a keyboard having depressable keys for controlling the perforating mechanism including circuits connecting the keyboard and perforating mechanism, additional circuits adapted to be completed under the control of said keyboard, a common terminal circuit for said magnets, means operable upon completion of the analyzing device circuits and said latter keyboard circuits for breaking said common return line when a character undergoing sensing in the analyzing device differs from the keys depressed at said keyboard, said means comprising a series of magnets selectively operable under the control of said sensing device and a second similar series of magnets operable under the control of said keyboard, said magnets being arranged in pairs, and a pair of normally closed contacts associated with each of said latter magnets and arranged in series, said common return line normally extending through said latter contacts in succession.

11. In a verifying apparatus for verifying perforated data on a record media produced from original data in corrected form on a similar second record media, an analyzing device adapted to sense perforations in the index point positions of the first record media including circuits adapted to be completed under the control of said sensing means upon sensing one or more perforations in a column, a perforating mechanism for perforating corrected data on the second record media including punch operating magnets

and punches therefor, a keyboard having depressable keys for controlling the perforating mechanism including circuits connecting the keyboard and perforating mechanism, additional circuits adapted to be completed under the control of said keyboard, a common terminal circuit for said magnets, means operable upon completion of the analyzing device circuits and said latter keyboard circuits for breaking said common return line when a character undergoing sensing in the analyzing device differs from the keys depressed at said keyboard, said means comprising a series of magnets selectively operable under the control of said sensing device and a second similar series of magnets operable under the control of said keyboard, said magnets being arranged in pairs, a pair of normally closed contacts associated with each of said latter magnets and arranged in series, said terminal circuit normally extending through a pair of contacts associated with one of said magnets and from thence through a pair of contacts associated with the other magnet with which it is paired and from thence through the contacts of each pair of magnets successively.

12. In a verifying apparatus for verifying perforated data on a first record media produced from original data in corrected form on a similar record media, an analyzing device adapted to sense perforations in the index positions of the first record media, a perforating mechanism for perforating corrected data on the second record media, a coding device for controlling the perforating mechanism, a keyboard having depressable keys for controlling the coding device, means operable from said keyboard for advancing said first record media through the analyzing device and the second record media through the per-

forating mechanism simultaneously, and means under the joint control of said sensing mechanism and the keyboard for rendering said perforating mechanism inoperative when a character undergoing sensing at said index positions of the analyzing device does not correspond with the operation of the keyboard.

13. In a verifying apparatus for verifying perforated data on a first record media produced from original data in corrected form on a similar record media, an analyzing device adapted to sense perforations in the index positions of said first record media including a plurality of circuits adapted to be completed under the control of said sensing means upon sensing one or more perforations in a column, a perforating mechanism for perforating corrected data on the second record media including perforating magnets having a common return circuit for the magnets, a coding mechanism including magnets having relay circuits under the control of said magnets, a circuit making and breaking device including a first series of magnets selectively energizable under the control of said sensing brushes and a second series of magnets energizable under the control of said relay circuits, said magnets being arranged in pairs and each pair including a magnet in the first series and a magnet in the second series, a normally closed contact for each magnet operable upon energization of the magnet to become opened, said return line being under the control of said circuit maker and breaker and leading through the pairs of contacts of each pair of magnets in series and through the successive pairs in series.
